METAL WORKING MACHINE

Carl C. Grøtnes, Park Ridge, Ill.

Application July 30, 1930. Serial No. 471,653

23 Claims. (Cl. 153—2.)

This invention relates to a metal working machine which is adapted to operate upon annular metallic objects, such as automobile wheel rims and it is more particularly directed to a machine for operating upon rims for wire wheels to form therein inwardly projecting sockets intended to receive the heads of wire spokes anchored in the rim.

One object of the invention is to provide a machine of simple and rugged construction in which an annular object such as a wire wheel rim may be quickly and efficiently shaped and sized.

Another object is to provide a machine of the character indicated having two sets of dies between which a rim is interposed, one set operating to chuck or hold the rim while the other set operates to form spoke sockets in the rim.

A further object is to provide in a machine of the character set forth an improved actuating means for the two sets of dies such that not only may the shaping and sizing operation be performed at a high speed, but it may be performed with a high degree of efficiency.

Another object is to provide such a machine embodying die-actuating means of such a character that undue strain on the parts of the machine is avoided even when extremely heavy working operations are performed.

Other objects and advantages will become apparent from the following description taken in connection with the accompanying drawings, in which:

Figure 1 shows a vertical central section of a machine embodying the invention in its preferred form, the machine being shown with the dies in their open or retracted positions.

Fig. 2 is a fragmental view similar to Fig. 1 showing the dies in their closed positions with a rim compressed therebetween.

Fig. 3 is a fragmental plan view of the cam shaft and the associated parts as viewed from the line 3—3 of Fig. 2.

Fig. 4 is a transverse sectional view taken substantially along the line 4—4 of Fig. 2 with the stroke-adjusting mechanism omitted for the sake of clearness.

Fig. 5 is a front elevational view of the machine as viewed from the line 5—5 of Fig. 1.

Fig. 6 is an enlarged fragmental section of the die blocks showing the means employed for forming sockets in the rims.

Fig. 7 is a fragmental section similar to Fig. 2 showing an alternative embodiment of the invention, the dies being shown in their closed positions.

Fig. 8 is a fragmental portion of Fig. 7 showing the parts of the actuating mechanism in the positions which they occupy at the beginning of a die-closing operation.

Fig. 9 is a fragmental plan view as seen from the line 9—9 of Fig. 7.

While I have shown in the drawings and will herein described in detail the preferred embodiment of my invention, together with one alternative embodiment thereof, it is to be understood that I do not thereby intend to limit the invention to the specific forms disclosed, but aim to cover all modifications and alternative constructions falling within the spirit and scope of the invention as expressed in the appended claims.

In pursuance of the foregoing and other objects, the invention as herein illustrated provides a power operated machine embodying an axially movable table having two annularly arranged sets of opposed, movable dies between which a rim may be compressed by radial movement of the opposed blocks toward each other, together with means operable in a uni-directional movement of the table and including cam surfaces coacting in the initial portion of such movement to cause outward radial movement of the inner dies to engage and hold the rim and at the same time to define the proper diameter for the rim, and toggle links operating in the continued movement of the table, while the coacting cam surfaces are relatively fixed, to cause inward radial movement of the outer blocks to form the sockets and compress the rim against the inner blocks so as to insure proper form and size in the finished rim.

One advantageous form of the invention is illustrated in Figs. 1 to 6 of the drawings and comprises a machine with a base or main frame 10 having an upwardly and forwardly inclined portion 11 of rectangular cross section (Fig. 4) terminating at its upper forward end in four arms 12 which project upwardly and forwardly from the four corners of the portion 11.

Positioned between the arms 12 and in a plane substantially perpendicular to the longitudinal axis of the inclined portion 11 is a movable work carrier or frame in the form of a table 13 supported for movement axially of the inclined portion 11 by a plunger-like slide 14 guided in a suitable slideway 15 formed in the portion 11. The slide 14 has a flanged hub 16 at the outer end, to which the table 13 is secured, and extending downwardly and rearwardly from this hub is a pair of spaced bars 17 adapted to engage the slideway 15 as shown in Figs. 1, 2 and 110

4. The slideway 15 in the form shown is formed by an upwardly opening rectangular recess (Fig. 4) in the frame portion 11, in which the slide 14 is retained by means of bars 18.

5. In the operation of the machine the table 13 is reciprocated to operate the various forming and sizing means, and to perform any other desired operation on the work; and to impart the desired reciprocation to the table a pair of spaced eccentrics 19 (Figs. 1, 2 and 3) are employed. 10 These eccentrics are carried by a shaft 20 suitably journaled in the lower end of the frame portion 11 and driven from a suitable power source (not shown) through speed reducing gears 20^a, 21, 21^a and 22. The eccentrics 19 are connected to the slide 14 by spaced links 23 pivoted to a cross head 24 slidably positioned between the two bars 17 of the slide, as shown in Fig. 4.

20. The forward stroke of the table 13 in the present instance constitutes the sole working stroke, and the forward movement of the cross-head 24 is accordingly positively transmitted to a cross-bar 25 (Figs. 1 and 2) which connects the two bars 17 of the slide 14. This is done through the medium of a wedge 26 interposed between the cross-bar 25 and the cross-head 24, the wedge being vertically adjustable by a screw device 27 so that the forward limit of the table movement may be adjusted. Rearward movement of the cross-head 24 is yieldingly communicated to the slide through a pair of transversely spaced bolts 28 (Fig. 1) which extend from the cross-bar 25 rearwardly through brackets 24^a fixed on the cross-head and have coiled springs 29 between the heads of the bolts 28 and the brackets 24^a to hold the head 24 yieldingly against the wedge 26.

30. To properly size and form an annular metal rim positioned on the table 13, two opposed, annularly arranged sets of radially movable die-carrying blocks are mounted on the forward side of the table, the expanding die blocks 30 of the inner set and the contracting die blocks 31 of the outer set being mounted for radial sliding movement upon the table. The inner die blocks 40 30 have flat base plates projecting outwardly to provide supports for the outer die blocks 31, interengaging grooves and projections on the blocks and the table serving to guide both sets of blocks for radial movement. The die blocks 30 are urged inwardly by springs 33 each held in place by two axial pins 34 respectively mounted in the die blocks 30 and suitable lugs 35 secured on the table.

45. In order that the machine may readily be adapted for various operations, each of the inner die blocks 30 has a suitable formed die 36 removably secured on its outer surface by tap screws 36^a while the outer die blocks 31 have complementary dies 37 secured thereto by tap screws 37^a.

50. Certain of the outer dies 37 may be provided with inset bosses 38 (Fig. 6) which will serve to form outwardly facing sockets 39 in a metallic rim 40, suitable recesses 41 being formed in the opposing dies 36 to receive the displaced metal. The bosses 38, together with their corresponding recesses 41 may be staggered so that the resulting sockets 39 will fall alternately in two transversely spaced planes as shown in Fig. 6.

55. The rims 40 intended to be operated upon are preliminarily shaped as by rolling, to a desired cross section, such as that shown in Fig. 6, the central portion of the rim, of course, being flat, that is without the sockets 39; and my improved machine is arranged automatically to actuate the

60. dies 36 and 37 in proper timed relation to chuck the rim, form the sockets therein and thereafter to press the rims to the proper size and correct any minor distortion which may have resulted from the socket-forming operation.

65. The outward chucking movement of the inner dies is accomplished in the initial forward movement of the table by coacting cams 50 and 51 as herein described, and thereafter inward movement of the outer dies occurs to shape the rim. Such inward movement of the outer dies 37 is preferably obtained by means of a plurality of toggle links 42 one of which is interposed between each of the die blocks 31 and a stationary abutment frame in the form for a ring 43 supported on the forward ends of the arms 12 of the main frame. As shown in Figs. 1 and 2, each toggle link 42 bears at its opposite ends on trunnions 44 and 45, the former being mounted in an outer bearing member 46 within the ring 43, and the latter being mounted in the outer die blocks 31. The toggle links are held in position by side links 47 connecting the ends of the opposed trunnions. By this construction the toggle mechanism is able to withstand tremendous pressure and will serve to effect movements of the outer die blocks 31 in both directions.

70. It will be understood that in the forward stroke of the table by the power driven eccentrics, the toggle links are moved from an inclined position (shown in Fig. 1) to a position substantially parallel with the table (Fig. 2); and that in such movement the outer die blocks are moved radially inwardly. However, before the outer dies reach the work performing portion of their strokes, the inner blocks must be moved radially outwardly to the position shown in Fig. 2 so as to engage with the rim interposed between the two sets of blocks, such outward movement being of a fixed length such that not only is the work engaged and held in operative position, but the dies are positioned so as to determine the true predetermined circumference of the rim when completed.

75. To obtain such outward radial movement of the inner dies 36, the coacting cams 50 and 51 are employed. The former is in the form of an annular abutment member positioned centrally with respect to the table 13 and adapted to be engaged by a plurality of cam shoes 51, one of which is mounted on each of the inner die blocks 30. The peripheral surface of the cam member 50, as shown in Fig. 5, is divided into a plurality of flat segments, one for each of the inner die blocks. These segments each slope gradually from the front toward the rear of the machine and the cam member 50 is therefore of tapered form, as shown in Fig. 1, having a plurality of similar cam surfaces 52 formed by the segments.

80. Upon relative movement of the cam 50 and the table 13, the engagement of the cam shoes 51 with the inclined cam surfaces 52 will cause radial expansion of the inner dies 36, and to obtain such relative movement the forward movement of the table is preferably utilized. Thus, when radial expansion of the inner dies is desired, the cam member 50 is held stationary while the table 13 is moved forward. It will be apparent that during such forward movement of the table the outer dies 37 will be moved radially inwardly by the toggles 42 and when the outer dies come into contact with the work a great inward force will be exerted upon the inner dies 36. This force produces great friction between the cam shoes 51 and the cam surfaces 52 and to avoid the neces-

sity for excessively large, cumbersome holding means for the cam member 50, means is preferably provided for holding the cam 50 stationary until the inner dies have been expanded to the desired diameter and arranged thereafter to permit movement of the cam member 50 with the table 13.

In the preferred embodiment illustrated in Figs. 1 to 4 this means is controlled and driven by the main shaft 20 of the machine and comprises a rod 53 detachably connected to the cam member 50 by means of a nut 54, and extending rearwardly and downwardly through the table 13 axially thereof. This rod 53 extends through 10 and is slidably mounted in the cross-bar 25 of the slide 14 and is connected at its rear end to a slide 55 mounted in the cross-head 24. The wedge 26 being between the cross-bar 25 and the cross-head 24, is slotted at 26^a to permit the 15 rod 53 to extend therethrough. The slide 55 is mounted in the cross-head 24 for sliding movement, and at its rear end which projects out of the cross-head it carries a yoke 56 which surrounds a cam 57 mounted on the main shaft 20 between the two eccentrics 19 (Figs. 1, 2 and 3). In the rear portion of the yoke 56 is a cam 25 roller 58 adapted to bear against the cam 57 in such a manner that the cam determines the forward extent of movement of the cam roller. The cam 57 has a dwell portion 59 which maintains the roller 58 against forward movement during the larger portion of the rotating movement of the shaft 20. At one side (Fig. 1) the cam 57 has a relieved portion 60 which permits forward 30 movement of the cam roller 58 after the table has been moved forward a predetermined distance.

While the cam member 50 is held stationary by the rotating cam 57, the forward movement of the table 13 causes the inner dies 36 to be expanded into chucking relation to the rim 40. The relieved portion 60 of the cam is then brought into engagement with the cam roller 58, as shown in Fig. 2, whereby to permit forward movement of the cam member 50 with the table 13. Thus the extremely large force exerted by the toggle links 42 cannot cause excessive strain upon the actuating mechanism of the inner dies.

Upon the return or rearward stroke of the table 13 the toggle mechanism will withdraw the outer dies 37 to the positions shown in Fig. 1 and as the cam shoes 51 move rearwardly along the converging cam surfaces 52 the springs 33 will force the dies 36 inwardly to the positions shown in Fig. 1 so that the finished rim may be withdrawn and a new rim put in place within the two sets of dies. During the retracting movement of the table the dwell surface 59 of the cam 57 will again be brought into operative relation with the roller 58 and the cam 50 will be retracted from the position shown in Fig. 2 to its initial position shown in Fig. 1.

It will be seen that the outside diameter of the inner or expanding dies 36 may be readily changed, within certain limits determined by the width of the dies, by substitution of a new cam 50, and that the inside diameter of the outer or compressing dies 37 may be changed by adjustment of the wedge 26 by means of the screw device 27. The screw device 27 may also be used to determine the amount of compression to be applied to the rims.

In Figs. 7, 8 and 9 of the drawings an alternative embodiment of the invention is illustrated.

In this machine the frame, the table construction and the mounting of the die blocks are generally similar to that shown in Figs. 1, 2, and 5 and these parts bear the same reference numerals as in those figures. The principal differences of construction are found in the actuating means for the inner dies 36, the cam member 50^a being provided with segmental cam surfaces 52^a each of these surfaces being composed of an inclined intermediate surface 52^a with dwell surfaces 52^b at each end thereof. Similarly the cam shoes 51 are each provided with an inclined surface 51^a having dwell surfaces 51^b at each end thereof.

In this alternative embodiment of the machine the cam 50^a is held stationary during the first portion of the forward movement of the table and thereafter released for movement with the table by means which is governed by the longitudinal movement of the table rather than by rotative movement of the shaft 20 as in the other embodiment.

The cam member 50^a is mounted on a rod 53^a which extends rearwardly and downwardly through the table 13 axially thereof and is journaled slidably at its rear end in a bearing sleeve 54^a mounted in the cross-bar 25 of the slide 14. Forwardly of the cross-bar 25 the rod 53^a carries a radially projecting collar 60^a which is fixed against longitudinal movement relatively to the rod 53^a.

To hold the rod 53^a against longitudinal movement the collar 60^a is engaged by a detent 61 which in the present case is in the form of an arm pivoted upon a horizontal axis at 62 on the inclined portion 11 of the frame above the slide-way 15. At its pivoted end the arm 61 is bifurcated as shown in Fig. 9 so as to extend around the adjusting device 27 of the wedge 26. The forward end of the arm 61 is provided in its lower surface with a notch 63 adapted to slip over the collar 60^a to hold the rod 53^a against movement. When the notch 63 in the arm engages the collar 60^a, and the table 13 is in its retracted position as shown in Fig. 8, a cross-bar 64 extending between the two bars 17 engages a flat upper surface 65 on the arm 61 and maintains the arm in operative relation to the rod 53^a.

As the table 13 is moved forward in the operation of the machine the bar 64 moves forwardly along the surface 65 of the arm and after it has passed beyond the rounded forward edge of the surface 65 the arm 61 may move upwardly to its inoperative position shown in Fig. 7, wherein the notch 63 is disengaged from the collar 60^a and the rod 53^a is free to move forwardly with the table 13.

During such forward movement of the table and prior to the release of the detent arm 61, the cam shoes 51 are moved upwardly along the inclined surfaces 52^a of the cam 50^a (which is now stationary) until the inner dies 36 are in the desired chucking relation to the rim. After the bar 64 has moved to its inoperative position shown in Fig. 7, the friction between the cam shoes 51 and the cam 50^a serves to pull the rod 53^a forwardly with sufficient force to cause the detent 61 to be thrown upwardly to its disengaged position. The cam 50^a may then move forwardly with the table so as to maintain the inner dies 36 in the desired positions during the performance of the working operation by the outer dies 37. During the final forward movement of the table all strain on the actuating mechanism of the inner dies is avoided since the cam member

50^a moves with the cam shoes 51 during this period.

When the movement of the table 13 is reversed the inward pressure of the springs 33 will cause sufficient friction between the cam shoes 51 and the cam 50 to move the cam and the rod 53^a rearwardly from the position shown in Fig. 7 to the position shown in Fig. 8. When the collar 60^a comes into registry with the notch 63, the 10 arm 61 will drop downwardly and the rear face of the notch 63 will limit the rearward movement of the rod 53^a. As the rearward movement of the table continues the cross-bar 64 will move over and into engagement with the surface 15 65 on the detent and will thus hold the detent in its operative position.

The machine herein described is unusually simple and efficient since it utilizes simple cam means for determining the diameter of the expanding dies 36 and for moving them to and maintaining them at this diameter, while efficient and powerful means in the form of toggle links are used for actuating the outer dies through their work-performing movements. The novel control 20 means for the cam 50 insures proper operation thereof and yet avoids all possibility of breaking of the machine due to the application of undue force upon the cam and its supporting means. Since the inner dies act principally to back up 25 the rim while the outer dies perform substantially all of the work, the efficiency of the machine will be obvious.

While I have herein described the machine as being adapted for sizing rims and forming outwardly facing sockets therein, it is to be understood that the invention is not limited to the performance of these operations only, it being obvious that other operations such as punching holes in the rim as desired may be performed.

40 This application forms a continuation in part of my copending application Serial No. 414,290, filed December 16, 1929.

I claim as my invention:

1. A machine of the character described comprising a stationary frame, a movable frame carried thereby, two annularly arranged sets of opposed die blocks mounted on one of said frames for radial movement toward and away from each other, cam means acting between one of said frames and the die blocks of the first set operable upon movement of the movable frame in a given direction to move the die blocks of said first set toward the other set to provide a backing of a predetermined diameter for an annular article, 50 and toggle links acting between the die blocks of the other set and said other frame and operable upon continued movement of said movable frame in said given direction to move the blocks of said other set toward and into operative relation to said first set to press an annular article positioned therebetween to the diameter determined by said first set of die blocks.

2. In a metal working machine of the class described, the combination of a frame having a central abutment, an outer annular abutment spaced radially from the central abutment, a support movable axially relative to said abutments, two sets of dies mounted on said support for relative radial movement and adapted to receive between them an annular piece of work, means for reciprocating the support, cam means operating as an incident to the movement of the support in one direction to impart radial movement to one of said sets of dies, and toggle means 70 also acting as an incident to the movement of

the support in the same direction to impart radial movements to the other set of dies.

3. In a metal working machine of the class described, the combination of a central abutment, a stationary frame member constituting a second abutment spaced radially from the central abutment, a support movable axially relative to said abutments, an inner set of die-carrying blocks arranged in circular series on said support and movable radially thereof, an outer set of radially movable die-carrying blocks also mounted on said support for radial movement, said central abutment and said inner blocks having coacting cam surfaces operable in the movement of the support to move said blocks radially to position and hold an annular piece of work encircling the blocks, and toggle means operable in the movement of the support and acting between said outer abutment and the outer series of blocks to cause the latter to move radially inwardly to shape and size the work. 95

4. A metal working machine of the class described, comprising a reciprocable support, two sets of die blocks mounted on said support for radial movement and for movement relative to each other, said two sets of dies being adapted to receive between them an annular piece of work to be operated upon, and actuating means for said dies including a cam means for one set of dies and a toggle means for the other set of dies. 100

5. A metal working machine of the class described, comprising a reciprocable support, two sets of die blocks mounted on said support for radial movement and for movement relative to each other, said two sets of dies being adapted to receive between them an annular piece of work to be operated upon, actuating means for said dies including a cam means for the inner set of dies and a toggle means for the outer dies, said cam and toggle means being operable to 110 compress the work between the dies, and a single means for actuating said cam and toggle means successively.

6. A rim forming and sizing machine comprising a frame and a table mounted for movement relatively to each other, two annularly arranged sets of forming dies mounted on said table for radial movement toward and from each other, the outer set of dies having bosses thereon arranged to form outwardly facing sockets in a metallic rim compressed between the two sets of dies, the inner set of dies having recesses therein to permit the formation of such sockets, cam means acting between said frame and the inner dies and operable during the first portion of a 125 relative movement of the frame and table in a given direction to move said inner dies outwardly to a given diameter, and toggle links between said frame and said outer dies and operable upon continued relative movement of said frame and 130 table in said given direction to force the bosses on said outer dies into a rim positioned between the two sets of dies.

7. A machine of the character described comprising a stationary frame, a movable frame carried thereby, two annularly arranged sets of opposed die blocks mounted on one of said frames for radial movement toward and away from each other, the die blocks of one set having bosses formed thereon, and the die blocks of the other set having recesses therein to receive said bosses, cam means acting between said recessed die blocks and the other one of said frames operable upon movement of said movable frame in a first direction to move said recessed die blocks 145 150

- toward the other die blocks to a given diameter, and toggle means acting between said other frame and said other die blocks operable by continued movement of said movable frame in 5 said first direction to move said other die blocks toward and into operative relation with said recessed die blocks. 80
8. A metal working machine of the class described comprising a frame having an annular 10 stationary ring and a central post, said ring being spaced outwardly from the post, a cam member secured to said post substantially in the plane of the ring, a table guided for reciprocation longitudinally of said post, an inner set of dies arranged in circular series about said cam member, an outer set of dies arranged in circular series about the inner set of dies, said two sets of dies being adapted to receive between them an 15 annular piece of work to be operated upon and being movable radially relative to each other, toggle links interposed between the outer dies and said stationary frame member, said inner dies having cam surfaces coacting with said cam member and operable in the movement of said 20 table in one direction to move the inner dies outwardly, and said toggle links being subsequently operated in the same movement of the table to move the outer dies inwardly. 90
9. A metal working machine of the class described comprising a stationary frame member and a central post, a table guided for reciprocation longitudinally of said post, an inner set of dies arranged in circular series on said table, an outer set of dies arranged in circular series about 25 the inner set of dies, said two sets of dies being adapted to receive between them an annular piece of work to be operated upon, and being movable radially relative to each other, toggle links interposed between the outer dies and said 30 stationary frame member, cam means operable in the movement of said table in one direction to move the inner dies outwardly, said toggle links being subsequently operated in the same movement of the table to move the outer dies inwardly, and means for varying the time of operation of the cam means relative to the toggle 35 means. 105
10. A rim forming and sizing machine comprising a frame and a table mounted for movement relatively to each other, two annularly arranged sets of dies mounted on said table for radial movement toward and from each other, the outer set of dies having bosses thereon arranged to form sockets in a metallic rim compressed between the two sets of dies and the inner set of dies having recesses therein to permit the formation of said sockets, a cam member mounted in said frame adapted in movement of the table in one direction relatively to the cam 40 to move said dies outwardly, means for moving said table in said direction, means to restrain said cam member against movement in said direction during the first part of the table movement and thereafter to permit movement of said cam member with said table, and toggle links acting between said frame and said outer dies during continued movement of said table to force said bosses on said outer dies into a rim positioned between the two sets of dies. 110
11. In a metal working machine, the combination of a frame and a table mounted for relative movement, a set of inner dies and a set of outer dies, each set being mounted on said table for radial sliding movement of the dies, toggle links 45 interposed between the frame and said outer dies operable upon relative movement of the table and the frame in one direction to move said outer dies inwardly, a cam member mounted centrally of said table and operable upon relative movement of said table and said cam member in said direction to expand said inner dies, and means operable to hold said cam member stationary relatively to said frame during relative movement of said table and said frame in said direction whereby to cause expanding movement of said inner dies, said last mentioned means being operable at a predetermined point in such relative movement of the table and the frame to release said cam member to permit said member to remain in fixed relation with respect to said table. 95
12. A machine of the character described comprising a frame, a table mounted in said frame for movement perpendicular to the plane of the table, a set of inner dies and a set of outer dies mounted on said table for radial movement toward and from each other, toggle links interposed between said frame and the outer dies and operable to move said outer dies inwardly upon movement of said table in one direction, a cam member mounted centrally with respect to said 50 table and arranged when said table moves past said member in said direction to act upon said inner dies to move the same outwardly, actuating means mounted on said frame for moving said table, and means operating in timed relation to said actuating means and operable to maintain said cam member stationary during initial movement of said table in said direction and after a predetermined movement of the table in said direction to permit movement of said member with the table. 100
13. A machine for operating upon annular articles, said machine comprising a frame, a table movably mounted on said frame, a pair of inner dies and a pair of outer dies, both mounted on said table for radial movement toward and away from each other, a cam member positioned centrally of the table and operable upon movement relatively to the table in one direction axially of the dies to expand said inner dies, means interposed between said frame and said outer dies and operable upon relative movement of the table and the frame to contract said outer dies, means operable to cause such relative movement of the frame and the table to contract the outer dies, and means operable to cause relative movement of said table and said cam member to expand said inner dies to a predetermined diameter to chuck a work piece before said outer dies contact the work piece, and thereafter to permit said cam member and said table to maintain the same relation until the outer dies are retracted. 115
14. A machine of the character described comprising a frame, a table mounted on said frame for movement perpendicular to the plane of the table, an annular set of inner dies and an annular set of outer dies mounted on said table in opposed relation for radial movement toward and from each other, means interposed between said frame and the outer dies operable upon movement of the table in one direction to move said outer dies inwardly, a cam member mounted centrally with respect to said table and arranged when said table moves past said cam member in 55 said direction to move said inner dies outwardly, actuating means for said table, and a cam operatively connected to said cam member and operable during the first portion of the table movement in said direction to maintain said cam member stationary and thereafter to permit said 120
15. In a metal working machine, the combination of a frame and a table mounted for relative movement, a set of inner dies and a set of outer dies, each set being mounted on said table for radial sliding movement of the dies, toggle links 60 interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 125
16. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 130
17. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 135
18. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 140
19. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 145
20. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move said outer dies inwardly, a cam member mounted centrally with respect to said table and arranged when said table moves past said cam member in said direction to move said inner dies outwardly, actuating means for said table, and a cam operatively connected to said cam member and operable during the first portion of the table movement in said direction to maintain said cam member stationary and thereafter to permit said 150

cam member to move with said table in said direction.

15. A metal working machine comprising, in combination, a frame and a table mounted for relative movement, an annular set of inner dies and an annular set of outer dies mounted on said table in opposed relation for radial sliding movement of the dies on the table, means interposed between the frame and said outer dies operable upon relative movement of the table and the frame in one direction to move said outer dies inwardly, a cam member mounted centrally of said table and operable upon relative movement of said member and said table in said direction 10 to expand said inner dies, a rotatable shaft operable in its rotation to cause relative movement of the table and the frame, a cam mounted on said shaft for rotation therewith, and a cam follower engaging said cam and connected to said cam member, said rotating cam having a dwell surface arranged to maintain said cam member stationary with respect to said frame during the initial portion of the relative movement of the frame and the table in said direction, said cam 15 also having a relieved portion arranged to permit relative movement of the cam member and said frame during a portion of the relative movement of the table and the frame.

16. A metal working machine comprising, in combination a frame, a table mounted on said frame for movement perpendicularly with respect to the plane of the table, an annularly arranged set of inner dies and an annularly arranged set of outer dies mounted on the table in opposed relation for radial movement of the dies, means interposed between the frame and the outer dies operable upon movement of said table in one direction to move said outer dies inwardly, a cam member disposed centrally of said table and operable upon relative movement of said cam member and said table in said direction to move said inner dies outwardly, a rotatable shaft operably connected to said table to reciprocate the same, a cam mounted on said shaft and a follower connected to said cam member and engaging said rotating cam to limit the movement of said cam member in said direction, said rotating cam having a dwell surface arranged to maintain said cam member stationary during the first portion of the movement of the table in said direction and also having a relieved portion to permit movement of said cam member with said table during further movement of said table in said direction, said cam 45 being operable upon continued rotation of said shaft to return said cam member to its initial position.

17. A metal working machine comprising, in combination, a frame, a table mounted on said frame for movement perpendicular to the plane of the table, annularly arranged sets of inner and outer dies mounted on said table in opposed relation for radial movement of the dies, means interposed between the frame and said outer dies operable upon movement of said table in one direction to move said outer dies inwardly, means for reciprocating said table, and means for expanding said inner dies comprising a cam member positioned centrally of said table and operable upon relative movement of said table and said cam member in said direction to expand said inner dies, a rod connected to said cam member and extending slidably through said table axially thereof, a lever arm mounted on said frame, interengageable means on the free end of said

arm and on said rod operable when engaged to fix said rod against longitudinal movement relative to said frame, and means moving with said table operable to engage said arm adjacent its free end to maintain said arm in operative engagement with said rod during a predetermined range of movement of said table.

18. In a metal working machine, the combination of a frame and a table mounted for relative movement, a set of inner dies and a set of outer dies, each set being mounted on said table for radial sliding movement of the dies, toggle links interposed between the frame and said outer dies operable upon relative movement of the table and the frame in one direction to move 85 said outer dies inwardly, a cam member mounted centrally of said table and operable upon relative movement of said table and said cam member in said direction to expand said inner dies, a detent mounted on said frame operable to hold 90 said cam member stationary with respect to said frame during relative movement of said frame and table in said direction, and means mounted in fixed relation to said table and operable to hold said detent in its operative position during 95 a portion of such relative movement of the frame and table and then to release said detent to permit the cam member to remain in fixed relation to said table during continued relative movement of the frame and the table. 100

19. A machine of the character described comprising a frame, a table mounted in said frame for movement perpendicular to the plane of the table, a set of inner dies and a set of outer dies mounted on said table for radial movement toward and from each other, toggle links interposed between said frame and the outer dies and operable to move said outer dies inwardly upon movement of said table in one direction, a cam member mounted centrally with respect to said 110 table and arranged when said table moves past said member in said direction to act upon said inner dies to move the same outwardly, actuating means mounted on said frame for moving said table, and a detent mounted on said frame 115 operable to maintain said cam member stationary during a predetermined movement of the table.

20. A machine of the character described comprising a frame, a table mounted in said frame for movement perpendicular to the plane of the 125 table, a set of inner dies and a set of outer dies mounted on said table for radial movement toward and from each other, toggle links interposed between said frame and the outer dies and operable to move said outer dies inwardly 130 upon movement of said table in one direction, a cam member mounted centrally with respect to said table and arranged when said table moves past said member in said direction to act upon said inner dies to move the same outwardly, actuating means mounted on said frame for moving 135 said table, a detent mounted on said frame and operable to hold said cam member against movement, and means mounted in fixed relation to said table and operable to maintain said detent 140 in its operative position during a predetermined range of movement of the table.

21. A machine of the character described comprising a frame, a table mounted in said frame for movement perpendicular to the plane of the 145 table, a set of inner dies and a set of outer dies mounted on said table for radial movement toward and from each other, toggle links interposed between said frame and the outer dies and operable to move said outer dies inwardly upon 150

movement of said table in one direction, a cam member mounted centrally with respect to said table and arranged when said table moves past said member in said direction to act upon said inner dies to move the same outwardly, actuating means mounted on said frame for moving said table, a detent mounted on said frame and operable to hold said cam against movement, and means acting in timed relation to the movement 10 of the table to control the operation of said detent.

22. In a metal working machine having a first die movable into backing-up relation to a work piece, a second die movable toward said first die to perform work upon a work piece backed-up by said first die, an actuating cam for moving said first die to its operative position, actuating means for said second die, and means for driving said actuating means operable to effect relative 20 movement of said cam and said first die until said first die is in its operative position and then

to terminate such relative movement, said driving means being operable after termination of such relative movement to move said second die through the work performing portion of its stroke.

23. In a metal working machine of the character set forth, the combination of a table having two sets of dies arranged in circular series on the table and adapted to receive between them an annular piece of work, and actuating means for each set of dies, and a power driven mechanism for said actuating means operable to effect first the operation of the inner dies into holding relation with the work and then the operation of the outer dies into engagement with the work, the actuating means for the inner dies including coacting cams moved relative to each other to effect the operation of the inner dies and held against relative movement during the operation of the outer dies.
